UNITED STATES PATENT OFFICE.

LAMAR H. SHOVER, OF MILWAUKEE, WISCONSIN, ASSIGNOR TO MILWAUKEE RELIANCE BOILER WORKS, OF MILWAUKEE, WISCONSIN.

LUBRICATING DEVICE

1,426,918.

Specification of Letters Patent. Patented Aug. 22, 1922.

Application filed March 14, 1922. Serial No. 543,547.

To all whom it may concern:

Be it known that I, LAMAR H. SHOVER, a citizen of the United States, and resident of Milwaukee, in the county of Milwaukee, 5 and State of Wisconsin, have invented certain new and useful Improvements in Lubricating Devices; and I do hereby declare that the following is a full, clear, and exact description thereof.

10 This invention pertains to an apparatus for lubricating movable parts of machinery, such as oscillating or reciprocating parts and the like.

15 The invention has primarily for its object to provide means such as a pad adapted to become saturated with oil fed thereto in any desired manner, thereby causing the various movable parts of a mechanism coming into contact with the pad to become properly 20 lubricated.

With the foregoing in view the invention consists in what is herein shown and described and more particularly pointed out and defined by the appended claims. While 25 I have shown and described one specific embodiment of the invention, it will be understood that various modifications and changes in the details of construction and arrangement of parts are contemplated as within 30 the scope of the appended claims.

In the drawings:

Figure 1 is a transverse sectional view illustrating one application of the invention, the same being taken on the line 1—1 of 35 Figure 2, and

Figure 2 is a sectional view taken on the line of 2—2 of Figure 1.

At the present time considerable difficulty is experienced in properly lubricating certain movable parts in various types of mechanisms, it being customary to either periodically oil such parts, or, in such cases as the mechanism permits, to direct a constant supply of oil to the same. Both of these 45 methods are objectionable, for the reason that in cases where the movable mechanism is oiled periodically, the same will quickly work out of the movable parts, leaving them dry. Furthermore, constant attention is required in this form of lubricating. In cases where the mechanism is lubricated by a constant feed, a great waste of oil is present.

The present invention, which is designed to overcome the foregoing disadvantages, is 55 applicable to various types of mechanisms,

and for the purpose of illustration, I have shown the same in connection with a pair of oscillating levers 1 journalled on a shaft 2, which is carried by a central bearing 3. The outer ends of the oscillating lever 1 have 60 pivoted thereto a pair of links 4 which are actuated by mechanism, not shown. In order to properly oil the shaft 2, the central bearing 3 is provided with an oil hole 5.

The present invention consists in the provision of a porous pad 6, which is preferably formed from a heavy layer of felt, or similar material, the same being positioned above the mechanism and supported by the central bearing 3 and oscillating arms 2. 65

In the present embodiment of the invention, I have shown the entire mechanism covered by a hood 7, which serves to carry an oil feed coupling consisting of a sight feed 8 provided with a regulating screw 9 70 which serves to regulate the feed. The oil feed coupling is provided with a threaded extension 10 extending through the hood and secured thereto by means of a nut 10'. It will be noted from the drawings that the oil 75 feed is positioned directly above the bearing 3 and in alinement with the oil hole 5. Thus as the oil drops from the feed coupling to the pad 6, the point of greatest saturation will be directly over the oil hole 5, and the 80 pad being in contact with the bearing 2 will, through capillary attraction, feed a steady supply of oil through the oil hole to the 85 shaft 2.

In operation the feed coupling is so regulated as to permit sufficient supply of oil to keep the entire pad 6 well saturated. Thus it will be seen that as the levers 1 oscillate, their ends will contact with the pad and will take off sufficient amount of oil to lubricate 95 the link connections.

Connecting the feed coupling and a source of oil supply, not shown, is a feed line 12 which is provided with the conventional type of oil filter 13 adapted to remove the heavy 100 particles from the oil, thus preventing the pad from becoming gummy or clogged. Adjacent the filter and positioned between it and the oil supply is a shut-off cock 14 which permits the supply to be cut off when it is 105 desired to clean the filter or remove the hood 7. As previously stated, the oil may be supplied by either a forced feed or by means of gravity.

From the foregoing, it will be seen that a 110

very simple and economical arrangement has been devised, whereby a small supply of oil may be distributed to a plurality of spaced, movable parts, the pad serving not only as a distributing means, but, also, acting to retain and feed only the required amount of oil, thus reducing the cost of oiling and at the same time eliminating wear upon the machine due to improper lubricating.

10 I claim:—

1. In combination with a mechanism consisting of a bearing, a shaft supported in said bearing; an oscillating lever carried on said shaft; a pad supported by said mechanism and adapted to intermittently contact with said oscillating lever, and means for supplying lubricant to the pad.

2. In combination with a mechanism consisting of a bearing provided with an oil hole, a shaft supported in said bearing, and an oscillating lever carried on said shaft; a pad supported by said mechanism and adapted to intermittently contact with said oscillating lever, and means positioned practically above said oil hole for supplying lubricant to the pad.

3. In combination with a mechanism consisting of a bearing, a shaft supported in said bearing, an oscillating lever carried on said shaft, and members operably connected to the ends of said lever; a pad positioned above and supported by said mechanism, said pad being adapted to intermittently contact with the end of said lever, and means for supplying lubricant to the pad.

4. In combination with a mechanism consisting of a bearing provided with an oil opening, a shaft supported in said bearing, an oscillating lever carried on said shaft, and a member operably connected to one end of the lever; a pad positioned above said mechanism and supported thereby, said pad being adapted to intermittently contact with the end of said lever, and means positioned above said pad and in vertical alinement with said oil hole for supplying lubricant to the bearing.

In testimony that I claim the foregoing I have hereunto set my hand at Milwaukee, in the county of Milwaukee and State of Wisconsin.

LAMAR H. SHOVER.
